United States Patent Office

Des. 191,793
Patented Nov. 21, 1961

191,793

TOY MILITARY TANK

Allan J. Alvaney, Arlington Heights, Ill., assignor to Sears, Roebuck and Co., Chicago, Ill., a corporation of New York

Filed Dec. 1, 1960, Ser. No. 63,056

Term of patent 3½ years

(Cl. D34—15)

FIG. 1 is a rear perspective view of the toy military tank showing my new design, and

FIG. 2 is a front perspective view of same.

The dominant features of my design reside in the portions shown in full lines.

I claim:

The ornamental design for a toy military tank, substantially as shown and described.
